C. D. Haskins

UNITED STATES PATENT OFFICE.

WILLIAM F. CRADDICK, OF SALT LAKE CITY, UTAH, ASSIGNOR TO VIT-O-NET
MANUFACTURING COMPANY, A CORPORATION OF CALIFORNIA.

ELECTRIC SWITCH.

1,300,126.

Specification of Letters Patent. Patented Apr. 8, 1919.

Application filed January 17, 1918. Serial No. 212,360.

To all whom it may concern:

Be it known that I, WILLIAM F. CRADDICK, citizen of the United States, residing at Salt Lake City, in the county of Salt Lake and State of Utah, have invented a certain new and useful Improvement in Electric Switches, of which the following is a specification.

My invention relates to improvements in electric switch and connectors for controlling multiple electric circuits, and the object of my invention is to provide an electric switch associated with a plurality of circuit connectors whereby any particular one, or any number of particular ones, or all of a plurality of electric circuits may be connected in multiple to and disconnected from the same source of electricity.

A further object of my invention is to provide a multiple electric switch and a plurality of circuit connectors in association with electrical resistance coils whereby a plurality of electric circuits of different resistance may be connected in multiple to and disconnected from the same source of electricity to cause substantially the same number of amperes of electricity to flow through each of said plurality of electric circuits notwithstanding the difference in the resistance of said circuits.

I accomplish these objects by devices illustrated diagrammatically in the figure of the accompanying drawing, wherein the numeral 1 designates a supporting base of material that is a non-conductor of electricity, upon which supporting base 1 is mounted four electrical switch contact members 2, 3, 4 and 5 which are disposed at equidistant points on a circular line.

Rotatably mounted on said supporting base 1 is a metal spindle 6 disposed with its axis concentric with the circular line of said contact members 2, 3, 4 and 5, and rigidly fastened to said spindle 6 at a point spaced from the front side surface of said base 1 is a switch member 7 made of springy sheet metal which is formed to have five integral electrical contact arms 8, 9, 10, 11 and 12 that extend radially therefrom in positions to adapt them each to make an electrical contact with all of the switch contact members 2, 3, 4 and 5 in response to a rotary movement of said spindle 6.

The angular distance between adjacent ones of the contact arms 8, 9, 11 and 12 is the same but the contact arm 10 is disposed

midway between the contact arms 9 and 11, whereby the spindle 6 may be rotatively moved to dispose the contact arm 10 to rest upon and make an electrical contact with any desired one of the contact members 2, 3, 4 and 5 without causing any of the contact arms 8, 9, 11 and 12 to rest in engagement with any other of said contact members 2, 3, 4 and 5, but when the spindle 6 is rotatively moved to dispose any one or more of the contact arms 8, 9, 11 and 12 to rest on any of the contact members 2, 3, 4 and 5 then the contact arm 10 will not be engaged with any of said contact members 2, 3, 4 and 5.

The spindle 6 may be rotatively moved in either direction by manipulating a disk-like knob 13 which is fastened to the outwardly projecting end portion of said spindle 6.

Fastened to the front surface of the supporting base 1 adjacent to its lower edge is a strip 14 of insulating material of rectangular cross-section through which strip 14 extend transversely a plurality of pairs of metal tubular sockets 15 and 16, 17 and 18, 19 and 20, and 21 and 22 which are rigidly supported by said strip 14 in positions spaced from each other.

All of the sockets 15, 17, 19 and 21 are electrically connected together by a conducting wire 23 that is connected by a conducting wire 24 to one member 25 of a pair of insulated conductors that are twisted to form a flexible cord to which is electrically connected a well known form of connector plug 26 that is adapted operatively to connect with an electric lamp socket, not shown.

The other member 27 of said pair of insulated conductors is in electrical connection with the springy sheet metal switch member 7.

The tubular sockets 16, 18 and 20 are respectively connected with the contact members 2, 3 and 4 through resistance coils 28, 29 and 30 while the tubular socket 22 is connected directly to the contact member 5 by a conductor 31.

Four double connector plugs 32, 33, 34 and 35 of well known form are adapted to be inserted respectively into the pairs of tubular sockets 15 and 16, 17 and 18, 19 and 20, and 21 and 22 to make electrical connections therewith in an obvious manner.

Electrically connected with each of the

double connector plugs 32, 33, 34 and 35 is a flexible double conductor cord, as conductor cords 36, 37, 38 and 39, respectively, which cords may be extended to and be 5 electrically connected with different translating devices 40, 41, 42 and 43 which are to be operatively supplied with an electric current at desired times.

The apparatus thus described may be advantageously utilized to control the supply 10 of electric current to electro-thermal garments which are wired for the diffusion of electric currents therethrough, and which are used for the temporary envelopment of 15 the body, the head, and the feet of an invalid to impart heat thereto in the operation of treating said invalid for rheumatism or other disease.

For instance, the translating device 40 20 may represent an electro-thermal cap adapted to envelop one's head, and devices 41 and 42 may represent electro-thermal socks for enveloping one's feet while the device 43 may represent a large electro-thermal robe 25 or coat for enveloping one's body, the heating element of which is of a resistance that adapts it to be properly heated by the constant potential current of an incandescent electric lamp circuit, while the heating elements 30 of the socks and cap are of lower resistance which may differ from each other, but the resistance coils 28, 29 and 30, which are respectively connected in the circuits with the socks and cap, are made to cause 35 said circuits to be each of the same resistance as is the circuit of the coat whereby the same number of amperes of current will flow through the heating elements of all the garments represented by the devices 40, 41, 42 40 and 43.

Manifestly, when the connector plug 26 is connected with an electric lamp circuit, and all of the double connector plugs 32, 33, 34 and 35 are connected with the pairs of tubular sockets 15 and 16, 17 and 18, 19 and 20, and 21 and 22 respectively, then the knob 45 13 may be manipulated rotatively to move the spindle 6 to cause the contact arm 10 to rest upon and connect with a required one of 50 the contact members 2, 3, 4 and 5 to connect the heating element of a desired one of the electro-thermal garments with said lamp circuit, or, as may be desired, to cause said

lamp circuit to be connected only with both of the contact members 2 and 3, or with 55 only the three contact members 2, 3 and 4, or with only the two contact members 4 and 5, or with all of the contact members 2, 3, 4 and 5, as may be required to conduct the same number of amperes of current to one, 60 more, or all of the heating elements of said garments as may be desired in an obvious manner.

If all of the translating devices are of the same resistance, the resistance coils 28, 29 65 and 30 will not be required in order to cause the same number of amperes of current to flow through the circuit of each of said translating devices.

Obviously, changes may be made in the 70 forms, dimensions and arrangement of parts of my invention without departing from the spirit thereof.

What I claim is:

An electric switch having separable double connectors, one member of each of which connectors consists of a double plug and the other member of each of which connectors consists of two insulated metal sockets; means for connecting one socket of each of 75 said double connectors with one terminal of 80 a source of electricity; a plurality of equally spaced electric contact members, a different one of which is in connection with the other socket of a different one of said connectors; 85 a plurality of integral electrical contact arms mounted on a rotatively movable spindle, one of which contact arms is adapted to be disposed to rest upon a desired one of 90 said contact members, while the others of 95 said contact arms are disengaged from the others of said contact members, in response to a rotative movement of said spindle; and the others of said contact arms being adapted to be disposed to rest each on a different one of said contact members in response to a rotative movement of said spindle; and means for connecting said integral contact arms with the terminal of said source of 100 electricity.

In witness whereof, I hereunto subscribe my name this 4th day of January A. D., 1918.

WILLIAM F. CRADDICK.

Witness:

C. W. JOHNSON.
